UNITED STATES PATENT OFFICE

HOWARD A. PHILLIPS, OF OTTUMWA, IOWA, ASSIGNOR TO OTTUMWA BOX CAR LOADER CO., OF OTTUMWA, IOWA, A CORPORATION OF IOWA

PORTABLE BOX CAR LOADER

Application filed January 15, 1930. Serial No. 420,891.

The object of my present invention is to provide a portable box car loader of simple, durable and inexpensive construction.

More particularly, it is my object to provide a small loader of light weight, which is freely mobile and can be moved from place to place by hand.

Still another object is to provide such a portable, freely mobile loader, having a pair of wheels, a frame thereon including upright members, and a spaced material receiving element, an endless conveyor pivoted on the part of the frame having the material receiving element and being mounted on said upright members for vertical adjustment, the material receiving portion of the frame having an adjustable supporting leg or the like.

Still a further object is to provide such a structure of this kind in which the endless conveyor is so supported that it may be vertically adjusted at its end and at a point intermediate its ends.

Thus it is my purpose generally to provide a portable loader including an endless conveyor capable of being operated at different speeds and adjusted to a very great variety of heights and angles.

Another purpose of my invention is to provide a structure which affords maximum strength for the loader, and which provides means for holding the loader against sideways swaying.

With these and other objects in view, my invention consists in the construction, arrangement and combination of the various parts of my portable box car loader, whereby the objects contemplated are attained, as hereinafter more fully set forth, pointed out in my claims, and illustrated in the accompanying drawings, in which:

Figure 1 is a top or plan view of my improved portable box car loader.

Figure 2 shows a side elevation of the same, parts being broken away.

Figure 3 is a detail, sectional view taken on the line 3-3 of Figure 1.

Figure 4 is a diagrammatic plan view, illustrating the manner of using my improved portable loader.

Figure 5 is a transverse, vertical, sectional

view taken on the line 5-5 of Figure 3; and Figure 6 is a detail, sectional view taken on the line 6-6 of Figure 5.

Generally speaking my improved portable loader consists of a frame, indicated generally by the reference numeral 10, mounted on a pair of wheels 12 and projecting rearwardly therefrom, and having at its rearward part a material receiving means, such as a chute 14.

An endless conveyor 16 is pivoted at the 60 chute portion of the device and projects forwardly above and between the wheels.

Referring now in greater detail to the structure under consideration, it will be observed that the wheels 12 are mounted on 65 and connected by an axle 18. The axle is journaled on a transverse angle bar 20 (Figure 3). Secured to the rear flange of the angle bar 20 is a transverse plate or bar 22. At the ends of the plate 22, uprights 24 of any 70 suitable material and shape, having the proper strength and weight are arranged.

Secured to and extending upwardly from the lower ends of the uprights 24 are substantially horizontal plates 26 (see Figure 2) 75 forming frame members, which connect with side plates 28 shown in Figure 2. The side plates extend upwardly and are connected near their rear upper edges by what may be called a back wall 30 (Figure 3).

Supported between the upper rear portions of the side walls 28 and at the upper part of the back wall 30 is the rear inclined wall 32 of a material receiving chute.

Secured to the upper edges of the side walls 80 28 are outwardly and upwardly inclined chute members 34, which have supporting arms 36 at their forward portions, which are rigidly secured to the respective uprights 24.

Supported between the frame members 26 90 on a connecting frame member 38 shown in Figure 3 is a motor 40.

The rear portion of the frame is adjustably supported by means of a supporting leg or the like 42, comprising a lower bar 42a and 95 upwardly extending arms 42b (see Figure 5). The arms 42b are provided with a series of holes 44 to selectively receive bolts 46, by which the supporting leg may be adjustably connected with the downwardly projecting 100

portions of the side walls 28. Instead of the supporting leg 42, casters may be used if desired.

At the upper ends of the uprights 24 are 5 mounted pulleys 48 for which there are provided guards 50.

On the rear parts of the side walls 28 are journaled the spindles 52 and 54 of a roller 56, having in its ends teeth 58 for the sprocket chains 60 of the conveyor 16, which will 10 be referred to below.

The roller 56 forms part of an endless conveyor having the bottom 62 and side walls 64. Relatively wide plates 66 are secured to 15 the rear ends of the side walls 64 of the conveyor 16 as indicated for instance in Figure 3.

The spindles 52 and 54 are journaled in bearing members 53 secured to the plates 66. 20 The bearing members 53 are pivotally mounted in flange members 55 secured to the side walls of the chute 14.

At the front end of the conveyor is an idler roller 68, having spindles 69 journaled 25 in brackets 70 adjustably mounted on the front ends of the side walls 64.

Chain guides 72 are secured to the lower parts of the plates 66 and extend forwardly below the endless conveyor 16 to form supports for the lower stretches of the chains 60.

The forward portions of the chain guides 72 are supported by braces 74 projecting downwardly from the sides 64 of the endless conveyor.

35 The forward roller 68 is provided with sprockets 76 for the chains.

The chains are connected by cross bars 78, which have flanges 80 between the chains to serve as scrapers or material engaging means.

40 A belt type conveyor may be used instead of cross bars and chains.

The brackets 70 are supported on the side walls 64 of the endless conveyor by means of adjustable bolts 82 extended through the 45 side walls 64 and through elongated slots 84 in the brackets 70, as shown in Figure 2 for example.

On the brackets 70 are suitable handles 86 used in manually moving the loader. 50 Each bracket 70 has in its rear part an outwardly projecting flange 88. Angle bars 90 are mounted adjacent thereto on the side walls 64 of the endless conveyor.

55 Adjusting screws 92 are threaded in the flanges of the angle bars 90 and bear against the flanges 88 for adjusting the brackets 70 in a well-known manner for thus tightening the chains 60.

60 It has already been noted that the rear end of the endless conveyor is pivotally mounted by the bearing members 53 pivoted in the flange members 55. I will now describe the manner in which the endless conveyor is adjustably mounted 65 on the uprights 24.

Secured to the chain guides 72 and extending transversely across below them and projecting beyond them is a cross bar 94, secured to which are eyebolts 96. Cables 98 extend from the eyebolts 96 upwardly and around the respective pulleys 48 and thence downwardly and around drums 100 on a transverse shaft 102 (see Figures 1 and 2). The shaft 102 is mounted in suitable brackets 104 carried by the frame members 26 (see Figure 2). On the shaft 102 is a worm wheel 106, which meshes with a worm 108 on a rod 110 suitably journaled on the frame of the machine as indicated in Figure 6.

70 The rod 110 extends rearwardly as shown in Figures 2 and 6 and has on its rear end a crank 112 by which it may be rotated for thus manipulating the drums 100.

75 The motor 40 is of the variable speed type and has a shaft 114, shown for instance in Figures 2 and 5. On the shaft 114 is a sprocket 116 on which travels a chain 118 extending over a sprocket 120 on the spindles 52 and 54 of the endless conveyor roller 56.

80 I shall now refer to the operation of my improved box car loader and thereafter set forth some of its advantages.

85 The box car loader can be moved by hand very readily from place to place.

90 The user can grasp one of the handles 82 (see Figure 2) and by pushing downwardly and moving the endless conveyor for instance from the full line position shown in Figure 2 to the dotted line position shown therein, the rear end of the loader can be lifted from the ground. The whole thing can then be moved about on the wheels 12 to the place where it is to be used.

95 In Figure 4, I have illustrated a loading platform 122 with a box car 124 adjacent thereto shown in diagrammatic form, and a gang plank 126 arranged between the loading platform and the box car.

100 If the far end of the box car is to be loaded, the loader may be moved clear to the inside of the box car and the material to be loaded may be supplied to the loader through the chute 125. The loader may be elevated conveniently for throwing the material, as may be desired, by manipulating the crank handle 112 and thus winding the cables 98 upon the drums 100 or releasing them as may be desired. Another adjustment may be had by removing the bolts 46 and placing them in different holes 44 in the leg 42.

105 There is thus provided a considerable range of adjustment for the loader. The speed at which the conveyor is operated may, of course, be regulated by means of the motor or gearing.

110 It will, of course, be understood that the material to be loaded is dropped upon the rear end of the conveyor after it is then carried to the forward end of the loader and thrown out. By elevating the forward end 115 of the conveyor, the material is caused to 120 fall off the conveyor and thus be thrown out. By elevating the forward end of the conveyor, the material is caused to 125 fall off the conveyor and thus be thrown out. By elevating the forward end of the conveyor, the material is caused to 130 fall off the conveyor and thus be thrown out.

and speeding up the conveyor chains, the material can be thrown quite a considerable distance.

After the ends of the box car are loaded, 5 the loader can be pulled out, and thus moved to any of the positions shown either in full lines or dotted lines in Figure 4, and of course, to many other positions.

In Figure 2, I have shown the endless conveyor provided with wear and guide plates 10 126, which will engage the uprights 24 and prevent any side swaying of the endless conveyor during its operation.

While I have referred to my loader as a 15 box car loader, it may be understood that it may be used for a great variety of material handling purposes, and I do not want to limit myself to its use for loading box cars.

Changes may be made in the construction 20 and arrangement of the various parts of my improved portable loader without departing from the real spirit and purpose of my invention, and it is my intention to cover by my claims, any modified forms of structure or 25 use of mechanical equivalents, which may be reasonably included within their scope.

I claim as my invention:

1. A portable loader of the class described, comprising supporting wheels, a frame carried thereby and projecting rearwardly from the wheels, a chute structure at the rear part of the frame, an endless conveyor including sides and a rear shaft, tubular bearings on said sides for said rear shaft, bearings on 35 said frame for said tubular bearings to pivot in, said conveyor receiving material discharged into the chute structure and projecting forwardly beyond the wheels, uprights on the frame forwardly of the pivot end of 40 the conveyor, and means for adjustably mounting the conveyor on the uprights.

2. A loader of the class described comprising a frame, a chute structure at the rear part of the frame, an endless conveyor including 45 sides and a rear shaft, tubular bearings on said sides for said rear shaft, bearings on said frame for said tubular bearings to pivot in, said conveyor receiving material discharged into the chute structure and conveying it away therefrom and means for adjustably mounting the conveyor for pivotal movement of said tubular bearings on said sides in said bearings on said frame.

Des Moines, Iowa, December 12, 1929.

HOWARD A. PHILLIPS.
